ILLUMINATING SYSTEM FOR TOY
HELICOPTERS

Calvin S. Cook, Erie, Pa., assignor to Louis Marx & Co., Inc., New York, N.Y., a corporation of New York
Filed Mar. 18, 1966, Ser. No. 535,397
10 Claims. (Cl. 46—228)

The present invention relates to toys and in particular to toy helicopters.

The present invention relates especially to a structure for providing illumination for toy helicopters.

One of the objects of the present invention is to provide a toy helicopter with an illuminating system which will be very entertaining to the operator of the toy.

In particular, it is an object of the invention to provide a toy helicopter with an illuminating system capable of describing a circle of light during rotation of the helicopter rotor.

Furthermore, it is an object of the invention to provide a helicopter with a structure capable of providing a multi-colored circle of light during rotation of the rotor.

Also, it is an object of the invention to provide an exceedingly simple and inexpensive and at the same time very rugged illuminating system for illuminating and extinguishing lamps carried by the rotor of a toy helicopter.

In particular, the objects of the invention include a structure which will make it very simple to turn the lamps on and off.

Also, it is an object of the invention to provide a structure which makes it very simple to replace a battery.

Primarily with the structure of the invention the toy helicopter will have at least one of its rotor blades provided with a lamp socket, while the rotor means which includes the latter blade carries a battery-support means which accommodates an electric battery. An electrical circuit means is also carried by the rotor means of the toy helicopter and electrically interconnects a battery carried by the battery-support means and the lamp socket, and this electrical circuit means includes a manually operable switch which can be closed by the operator for purpose of illuminating a lamp carried by the lamp socket and which can be opened for the purpose of extinguishing the lamp.

The invention is illustrated by way of example in the accompanying drawings which form part of the application and in which:

FIG. 1 is a perspective schematic illustration of one possible embodiment of a toy helicopter provided with the structure of the invention;

FIG. 2 is a longitudinal fragmentary sectional elevation, taken along line 2—2 of FIG. 1 in the direction of the arrows, and showing, on an enlarged scale as compared to FIG. 1, the details of the structure of the invention in association with the rotor of the toy helicopter;

FIG. 3 is a transverse section of the structure of FIG. 1 taken along line 3—3 of FIG. 1 in the direction of the arrows, and showing not only rotor details but also the drive means for the rotor;

FIG. 4 is a transverse section of a rotor blade, taken along line 4—4 of FIG. 1 in the direction of the arrows, and showing how a lamp is carried by the rotor;

FIG. 5 is an end view of the switch and battery-support means of the invention, taken along line 5—5 of FIG. 3 in the direction of the arrows; and

FIG. 6 is a wiring diagram of the electric circuit used in the particular embodiment illustrated in the drawings.

Referring now to FIG. 1, there is shown therein a toy helicopter 10 which can have any suitable construction. In the illustrated example the toy helicopter 10 includes a fuselage 12 and landing runners 14. The interior of the

2

fuselage 12 accommodates a source of power 16 which is diagrammatically illustrated in FIG. 1 and may take the form of any spring motor, capable of being manually wound in any suitable way, or an electric motor.

Situated over the fuselage 12 is the rotor 18 which includes the central hub 20 (FIG. 2) as well as a pair of opposed rotor blades 22a and 22b. As is apparent from FIG. 1 as well as FIG. 4, these rotor blades are inclined so as to give a screw action which will elevate the toy when the rotor 18 is driven.

10 In accordance with the invention the rotor blades 22a and 22b carry adjacent their outer tips a pair of lamp sockets for receiving lamps 24a and 24b, respectively. FIGS. 2 and 4 illustrate the lamp socket 26a which receives the lamp 24a in a removable manner as through a threaded or bayonet connection, well known in the art. A similar socket is carried by the blade 22b adjacent its outer tip to removably receive the lamp 24b.

15 A battery-support means 28 is carried by the hub 22 of the rotor means 18 for supporting a battery 30 in the form of a simple cylindrical dry cell readily available on the market. Thus, the support means 28 takes the form of a cylindrical casing 32 which can be made of any suitable electrically non-conductive material such as a plastic molded integrally with the blades 22a and 22b, as is indicated in FIG. 3. This casing 32 of the battery-support means 28 has an open end capable of being removably closed by a plastic cover 34 which has an outer circular flange surrounding the open end of the casing 32 and freely turnable thereon. For this purpose the flange of the cover has at its free edge an inwardly directed lip received in a groove of the casing 32, and the cover 34 is flexible and springy so that it can be snapped to and from the position shown in FIG. 3 for closing the casing 32. Thus, in order to replace the battery 30 it is only necessary to remove the cover 34, replace an exhausted battery with a fresh battery, and then place the cover 34.

20 An electrical circuit means is provided for electrically interconnecting the lamp sockets with the battery-support means 28 in such a way that a battery carried by the latter can be placed in electrical communication with lamps carried by the sockets. The circuit means includes a pair of wires 36 electrically connected with the socket 26a. These wires are accommodated in the blade 22a in an opening formed at its underside in the manner shown in FIG. 4. If desired, these wires can be embedded directly in the material of the blades during molding thereof. The wires 36 are embedded in the hub 20 in the manner shown in FIGS. 2 and 3. Also embedded in the plastic material which forms the casing 32 is a rear contact 38 directly engaged by one of the conductors 36 and a front contact 40 directly engaged by the other of the contacts 36. The rear contact 38 is exposed in the interior of the casing 32 so as to be pressed against by the rear end of the battery 30. The contact 40 is exposed at the outer periphery of the casing 32 adjacent its front open end.

25 The cover 34 has a central contact portion 42 which directly engages the front contact 40 of the battery, and this central contact 42 is in engagement with a contact 46 carried by the cover 34 for turning movement therewith. This contact 46 has a free end portion 47 which overlaps the exterior periphery of the casing 32 at its open end so that when the cover 34 is turned to a given angular position the contact 46 will have its portion 47 in slidably engagement with the contact 40, thus completing a circuit through the lamp 24a. In the same way the conductors which are connected to the socket which carries the lamp 24b are electrically connected with the contacts 38 and 40, so that in this way the turning of the cover 34 to the position placing the contacts 46 and 40 in engagement with each other will close the circuit to the lamp 24b simul-

taneously with the closing of the circuit to the lamp 24a. As may be seen from the wiring diagram of FIG. 6, closing of the single switch 40, 46 will result in simultaneous illumination of the lamps 24a and 24b. This closing and opening of the switch is brought about simply by turning the cover 34. In order that the operator may know when the switch is closed, the casing 32 of the support means 28 carries at its exterior a stationary index 48 cooperating with a turnable index 50 carried by the rotary cover 34 so that when the index 50 is aligned with the index 48 the operator will know that the switch is closed while when the index 50 is out of line with the index 48 the operator will know the switch is open. In this way if it should happen that with the closing of the switch the lamps are not illuminated, the operator will know that the battery needs to be replaced, or it may be that the lamps require replacement.

The pair of lamps 24a and 24b are preferably of different colors so that when the helicopter rotor is turned they will describe circles of light of different colors, providing a very entertaining effect.

The drive means for the rotor 18 includes a transmission extending from the motor 16 to the rotor. Thus, this transmission includes the pinion 52 directly driven from the motor 16 and meshing with a gear 54 which is connected with a drive shaft 56 connected directly to the hub 20 of the rotor. The drive shaft 56 is prevented from moving axially in the bearing 58 of the fuselage (FIG. 3) by any suitable collars or the like fixed to the shaft 56.

Thus, with the structure of the invention when the operator closes the single switch 40, 46 both of the lamps will be illuminated and when the drive means is actuated the turning rotor will describe multi-colored circles of light providing an exceedingly entertaining illuminating system.

What is claimed is:

1. In a toy helicopter, rotor means having a hub and a plurality of blades radiating therefrom, a lamp socket carried by at least one of said blades, battery-support means carried by said rotor means, for supporting an electric battery, and electrical circuit means carried by said rotor means and electrically interconnecting said socket and a battery carried by said support means, said circuit means having a manually operable switch for closing a circuit to illuminate a lamp in said socket and for opening said circuit to extinguish said lamp.

2. The combination of claim 1 and wherein said bat-

tery-support means and said switch are located at said hub.

3. The combination of claim 2 and wherein said lamp socket is situated adjacent an outer tip of said blade.

4. The combination of claim 2 and wherein said support means includes an elongated casing for receiving a battery, said casing having a removable cover.

5. The combination of claim 4 and wherein said cover is turnable with respect to the remainder of said casing, and said manually operable switch including one contact carried by said casing and another contact carried by said turnable cover so that when the latter is in one angular position said switch will be closed when said cover is turned to another angular position said switch will be open.

10 6. The combination of claim 5 and wherein an indicating means is carried by said casing and cover for indicating to the operator when said switch is opened and closed.

20 7. The combination of claim 1 and wherein a second socket is carried by a second rotor blade for mounting a second lamp on said second blade, said electrical circuit means electrically connecting said second socket with a battery carried by said support means, and said switch closing the circuit to the second socket simultaneously with the closing of the circuit to the first-mentioned socket.

25 8. The combination of claim 7 and wherein a pair of lamps of different colors are respectively carried by said sockets.

30 9. The combination of claim 8 and wherein a drive means is operatively connected with said rotor means for rotating the latter, so that when said lamps are illuminated a pair of differently colored circles of light will be described by the driven rotor means.

35 10. The combination of claim 1 and wherein a drive means is operatively connected with said rotor means for rotating the latter to describe a circle of light with an illuminated lamp carried by said socket.
